(57) CLAIM

The ornamental design for a divider, as shown and described.

DESCRIPTION

FIG. 1 is a front perspective view of the present invention.

FIG. 2 is a top plan view of FIG. 1.

FIG. 3 is a front elevation view of FIG. 1, the rear elevation view being a mirror image thereof.

FIG. 4 is a left side elevation view of FIG. 1, the right side elevation being a mirror image thereof; and,

FIG. 5 is a bottom plan view of FIG. 1.

The broken line showing is included for the purpose of illustrating and forms no part of the claimed design.

The present invention is a design for a golf divider with alternative design and support shapes.
